UNITED STATES PATENT OFFICE.

CRAIG RITCHIE ARNOLD, OF SHARON HILL, PENNSYLVANIA.

CAR-LIGHTING APPARATUS.

SPECIFICATION forming part of Letters Patent No. 366,292, dated July 12, 1887.

Original application filed March 29, 1886, Serial No. 196,953. Divided and this application filed February 1, 1887. Serial No. 226,140. (No model.)

To all whom it may concern:

Be it known that I, CRAIG RITCHIE ARNOLD, a citizen of the United States, and a resident of Sharon Hill, in the county of Delaware and State of Pennsylvania, have invented 5 certain new and useful Car-Lighting Apparatus, of which the following is a specification.

My invention relates, generally speaking, to appliances for lighting railway-cars by electricity, and has special reference to combinations of apparatus for this purpose, in which a dynamo-machine is employed for generating the electricity and a steam-engine is utilized as the active power for the dynamo, said 15 steam-engine being supplied with steam from a boiler and furnace with which a liquid fluid—such as a hydrocarbon oil—is employed.

The object of my invention is to increase the efficiency of such an apparatus and to prevent 20 unsteadiness in the lights arising from the motion of the car, and any consequent disturbances of the mechanical connection between the engine and the dynamo which would cause irregularity in the rotation of the dynamo-armature.

A further object of my invention is to couple the engine and the dynamo in such way that the running of the dynamo shall not be attended by the disagreeable noise which would 30 follow from the employment of mechanical connections—such as belts provided with belt-tighteners—and at the same time to secure an efficient mechanical connection of the two.

The invention consists in the novel combinations of appliances and the improved details 35 of construction, whereby the above and other objects are attained, and which combinations and improvements will be first described in connection with the accompanying drawings, 40 and will be then more particularly specified in the claims.

Figure 1 is a side elevation of an apparatus embodying my invention. Fig. 2 is a side elevation of the dynamo, and illustrates in detail 45 the means for transmitting the power from the engine-shaft to the dynamo in such way that the dynamo may be run without noise.

Fig. 3 is a plan illustrating the relative location of the apparatus, but with a steam-engine 50 of different form from that shown in Fig. 1.

Fig. 4 is a longitudinal section of a railway-car showing the lighting apparatus in place. C indicates the car-floor, and B¹ B² the walls of a compartment at one end of the car. These walls are made of suitable material, or are 55 suitably constructed, so that they shall be non-conductors of heat and of sound.

The compartment is divided into two chambers by the partition H, which is also constructed or formed so as to be a non-conductor 60 of heat. In one of these chambers is located the dynamo D, while in the other are placed the steam-engine, the water-supply tank, and the boiler and furnace. The object of this arrangement is to shield the dynamo from the heat, so 65 as not to interfere with its efficiency, heat being, as is well known, detrimental to the efficiency of a dynamo-machine. Without such non-conducting partition or shield H the dynamo, being confined in the same compartment with the furnace and steam-engine, would 70 be heated considerably and its efficiency correspondingly reduced.

The boiler from which steam is supplied to the engine is indicated at B. This boiler may 75 be of any kind in which steam is generated by a furnace supplied with fuel, consisting of a hydrocarbon oil supplied by means of an atomizer by steam, air, or other gas under pressure, after the manner shown in patent to A. M. 80 Shipman, No. 304,365. Other forms of hydrocarbon furnace and boiler in which an inflammable liquid is atomized and burned to heat the boiler would be suitable for the purpose 85 of my invention.

H² indicates the atomizer, which is connected through a regulating cock, I, with the steam space or coils of boiler B, so that steam under pressure may be supplied to said atomizer, and may act to spray or atomize the liquid hydrocarbon drawn from a tank, T.

F indicates the combustion-tube, through which the flame of the sprayed oil is introduced into the furnace beneath the boiler. A series of such atomizers and tubes may be employed, as indicated in Fig. 3. It is obvious 95 that the action of the furnace and boiler depends upon the supply of steam or its equivalent to the atomizer.

In order to start the boiler, I use compressed 100

air introduced into the steam-space of the boiler through a tube, H^2 , which latter is connected to the air-brake pipe L^2 beneath the car. The tube H^2 is provided with a suitable 5 cock for cutting off the air when desired, or for admitting it into the boiler-space and thence through the cock I, and to the atomizer, when it is desired to start the boiler and engine.

U indicates the escape-flue, and P the pipe 10 for exhaust-steam from the engine E.

A^2 is a pipe conveying steam from the boiler to the engine.

The tank W is placed in the chamber containing the boiler and engine, in order that the 15 water may be heated as far as possible before its introduction into the boiler, and the waste heat from the combustion of the oil and the operation of the boiler and furnace may be utilized as far as possible. The water from the 20 tank W is introduced to the boiler through the action of a feed-water regulator, P^2 , of any desired kind. The tank T, containing the hydrocarbon oil, is placed beneath the car-bottom, so as to be sheltered from the heat of the boiler 25 and furnace as far as possible, and so that, further, it may be kept cool by exposure of air outside the car. By this relative arrangement of the boiler and furnace and the oil-tank I entirely avoid any danger of explosion of the 30 oil-tank from overheating.

When a hydrocarbon fuel is employed in a car and is supplied through a pipe leading from the oil-tank to a suitable atomizer, there is danger of an interruption of the combustion 35 or flame at the mouth of the atomizer through an interruption of the supply of oil, caused by motion of oil in the tank and the momentary uncovering of the end of the tube leading from said tank and supplying 40 oil to the atomizer. In order to avoid this difficulty I employ a series of vertical diaphragms or partitions, G^2 , having perforations or openings that will permit a slow circulation of oil to the section into which the sup- 45 ply-pipe dips, but will prevent a swashing or movement of the body of oil as would be liable to uncover the end of the supply-tube and interrupt the supply of oil to the atomizer.

The engine E may be of any desired construction, but is preferably a high-speed engine. On the engine-shaft is placed wheel E^2 , which is in frictional connection with the wheel F^2 on the armature-shaft of the dynamo-machine D. The latter machine may be of any 55 desired construction, and has its commutator-brushes connected, as more clearly shown in Fig. 3, with a series of electric lights, K^2 K^2 , distributed through the car and deriving current from the supply-conductors in multiple 60 arc. One of the wheels of the friction-gear E^2 F^2 is covered with rubber, or has any other suitably-formed elastic facing which will tend to compensate for any inaccuracies in the surface of the other friction-wheel. The latter 65 wheel has a periphery formed of papier-maché or other suitable non-resonant material.

In order to keep the friction-wheels trans-

mitting power to the dynamo in constant connection, I propose to mount the dynamo on a suitable pivotal support, pivoted at C^2 , and to connect with the dynamo a spring, G, which shall tend to hold or pull the whole machine over in a direction to keep the wheels E^2 F^2 in constant frictional connection. It will be observed that the engine-shaft is located beneath and the dynamo-shaft above, and in such relation thereto that the wheel E^2 on the dynamo-shaft makes contact with the wheel F^2 on the upper half of the latter wheel and on the up-moving side of the latter, so that the 75 dynamo is in a neutral field, and the wheels will tend to press more closely into contact as the speed is increased. This means of driving a dynamo on a railway-car is not only an efficient way of transmitting the power from 80 the driving-engine, but possesses the additional advantage that it is noiseless, and that there is less liability to interruption of the 85 mechanical connection between the power and the armature-shaft than would be the case 90 with a pulley provided with a belt-tightener, since in the latter instance the jumping of the belt-tightener, owing to motion of the car, would cause slackening of the belt and slipping of the same. My arrangement also occupies less 95 space than a belt and admits of a high speed being attained in the dynamo.

I may employ, if desired, in addition to the appliances described, an air-pump, N^2 , connected with the steam-boiler space. This 100 pump may be employed for producing pressure in the boiler when it is desired to start the atomizer. This pump is designed more especially for use when the car is uncoupled from the engine. 105

When the car is on a train made up and connected to the locomotive, the air-pressure in the air-brake pipe L^2 may be utilized for starting the boiler by simply turning the cock in pipe M^2 and then applying match to the 110 atomizers.

The non-conducting walls B^2 B^2 and the partition H may be made double and filled with mineral wool or other non-radiating and noise-subduing material. 115

My present application is a division of a prior application filed by me March 29, 1886, Serial No. 196,953; and I do not claim herein the special form of furnace or boiler or the construction of the non-conducting compartment or other matter shown and described, as those matters are reserved for my said prior application and division thereof. 120

What I claim as my invention is—

1. In a lighting apparatus located in a railway-car, the combination of a dynamo-machine connected to an electric circuit on the car, a driving-engine, and a friction driving device, consisting of wheels secured, respectively, to the engine-shaft and the dynamo, and faced, as described, one with an elastic material and the other with a non-resonant material, such as papier-maché, substantially as described. 125 130

2. In a lighting apparatus located in a railway-car, the combination, with the driving-engine located in one compartment, of a dynamo-machine and a friction driving device, 5 consisting of wheels secured, respectively, to the engine-shaft and the dynamo, one of said wheels being covered with a non-resonant material, and all located in a compartment which is a non conductor of sound, substantially as 10 specified.
3. In a lighting apparatus located on a railway-car, the combination, with a driving-engine located in one compartment, of a dynamo and a friction driving device therefor, consisting 15 of wheels secured, respectively, to the engine-shaft and dynamo, and faced, as described, one with an elastic material, such as rubber, and the other with a non-resonant material, such as papier-maché, all located in a compartment 20 which is contiguous to the driving-engine compartment and whose walls are non-conductors of sound, substantially as specified.
4. The combination, with a dynamo and its driving-engine, of a friction driving device, 25 consisting of wheels secured, respectively, to
- the engine-shaft and the dynamo-shaft, said dynamo-shaft being arranged above the engine-shaft and on the side, said dynamo-shaft being arranged above the engine-shaft and on the upwardly-moving side of the latter, as and 30 for the purpose set forth.
5. The combination of a dynamo-machine mounted on a pivoted support, a driving-engine, a friction driving device, consisting of wheels secured, respectively, to the engine- 35 shaft and dynamo-shaft, said dynamo-shaft being arranged above the engine-shaft and on the side, said dynamo-shaft being arranged above the engine-shaft and on the up-moving side of the latter, and a spring tending to hold 40 or pull the dynamo in a direction to keep the friction-wheels in contact, as and for the purpose described.

Signed at Chester, in the county of Delaware and State of Pennsylvania, this 25th day 45 of January, A. D. 1887.

CRAIG RITCHIE ARNOLD.

Corrections in Letters Patent No. 366,292.

It is hereby certified that in Letters Patent No. 366,292, granted July 12, 1887, upon the application of Craig Ritchie Arnold, of Sharon Hill, Pennsylvania, for an improvement in "Car-Lighting Apparatus," errors appear in the printed specification requiring correction, as follows: On page 3 the words "said dynamo-shaft being arranged above the engine-shaft and on the side," should be stricken out from lines 26, 27, and 28, and also from lines 36, 37, and 38; and that the Letters Patent should be read with these corrections therein that the same may conform to the record of the case in the Patent Office.

Signed, countersigned, and sealed this 26th day of July, A. D. 1887.

[SEAL.]

D. L. HAWKINS,
Acting Secretary of the Interior.
